UNITED STATES PATENT OFFICE.

HOWARD K. DUTCHER, OF VANCOUVER, BRITISH COLUMBIA, CANADA.

FLUME.

1,413,528.

Specification of Letters Patent. Patented Apr. 18, 1922.

Application filed September 1, 1921. Serial No. 497,481.

To all whom it may concern:

Be it known that I, HOWARD K. DUTCHER, a citizen of the Dominion of Canada, and resident of Vancouver, in the Province of 5 British Columbia, have invented certain new and useful Improvements in Flumes, of which the following is a specification.

This invention relates to an improved construction in metal flumes, such as are used 10 for the conveyance of water or the like and particularly concerns that class of flume which is substantially semicircular in cross section.

The improvements are directed to a means 15 for securing the edges of the flume proper to the stringers of the frame in which the flume is carried, whereby the cross section area and therefore the carrying capacity of the flume is increased by the greater part 20 of the depth of the stringers.

The invention also includes a means for securing the joints of the flume section, which also provides a means for suspending the flume from the stringers.

25 The means by which these several results are attained are fully set forth in the following specification reference being made to the drawings by which it is accompanied, in which:

30 Fig. 1 is a cross section of the flume showing the connection of its edges to the stringers the left hand half section being taken through the joint, while the right hand half section is taken away from the joint.

35 Fig. 2 is an enlarged detail of the edge joint to the stringer.

Fig. 3 is a longitudinal section of the flume showing the joint connection of adjacent lengths, and in elevation the means for 40 tightening the joint bands.

Fig. 4 is a vertical section to an enlarged scale of the joint tightening and securing means.

Figs. 5 and 6 show in face and edge view 45 the cotter engaging projection of the outer joint tightening band.

Figs. 7 and 8, similar views of the same on the inner band.

Figs. 9 and 10, face and edge views of an 50 alternative cotter engaging projection on the outer band; and

Figures 11 and 12 are respectively face and edge views of the cotter engaging projection on the inner band. Figure 13 is a 55 detail view, partly in section, showing the

cotter wedge attached to bolt and engaging band projection.

The flume proper is composed of a series of thin, semicylindrical shells 2, preferably of non-corrodible sheet metal, the ends of which overlap one another and the overlapped ends are drawn into jointing contact with one another by bands 3 and 4 around the inner and the outer sides of the overlap.

The edges of the flume shell 2 are jointed to the lower part of the stringers 8 between which the flume is carried, in the manner illustrated in Figs. 1 and 2. A folded strip 5 of tarred felt or other suitable material is passed with the fold uppermost, half of 70 its width over the edge of the flume on each side and a batten 6 is secured with nails or screws to the stringer, which batten holds the edge of the flume with its felt jointing material 5 tightly into contact with the inner face of each stringer 4.

The greater part of the depth of the stringers is thus embodied in the cross sectional area of the flume and its carrying capacity, as indicated by the line 7 of the 80 water level, is considerably increased.

The joint bands 3 and 4 of the flume lengths are tightened on the overlapped joint by a bolt 9 through each of the stringers 8 in or adjacent their neutral axis, which 85 bolts also pass through elongated apertures 11 and 12 respectively in each end of the joint bands 3 and 4. Each bolt 9 passes also through an elongated aperture 13 lengthwise disposed in a tapered cotter 10 introduced 90 between the ends of the band to be movable in a plane parallel to the faces of the bands and normal to their edges.

The lower edge of this cotter 10 engages an inward projection 15 from the lower end 95 of the aperture 11 of the inner band 3, which aperture is elongated upward therefrom, and the other edge of the cotter engages an inward projection 16 from the upper end of the aperture 12 of the outer band 4 and is 100 elongated downward.

With this provision both ends of the joint bands 3 and 4 may, by driving the cotters 10 between the projections 15 and 16, be respectively endwise moved in opposite directions, 105 the inner one 3 being compressed downward on the overlapping joint of the flume lengths while the outer one 4 is drawn upward to tighten on the outer side of the overlapping ends of the same.

While the cotters 10 are being driven to effect this tightening, the ends of 3 and 4 are tightly held against the faces of the cotted by a washer under the ample head of 5 the bolt 9, which bolt may afterwards be further tightened to secure the cotted 10 against backward movement.

Instead of the cotted engaging projections 15 and 16 of the bands 3 and 4 being, 10 as shown in Figs. 5, 6, 7 and 8, viz., sheared or pressed along the sides and inwardly bent from the plane of the bands into the plane of the cotted, a piece 17 may be spot-welded or otherwise secured across the 15 entire width of the inner band 3, as shown in Figs. 11 and 12, and the end of 4 may be doubled over toward the inner side, as at 18, and spot-welded, as shown in Figs. 9 and 10 to provide effective engaging projections for the cotted 10.

As set forth in the preamble, the jointing of the edges of the flume 2 to the lower inner sides of the stringers 4 between which the flume is carried, increases considerably the 25 carrying capacity of the flume without any material increase in the cost of the same. The manner of connection is such as will enable a flume length to be readily removed, when necessary, as the joint securing nails 30 or screws do not pass through the material of the flume 2.

The manner of tightening the inner and outer covering bands on the overlapping joints of the flume lengths, forms a simple 35 and effective means for attaining the desired object: The wedge action being applied as directly as possible to the bands and in a plane parallel therewith, there is only a very slight bending moment on their 40 ends, which moment is fully met by the resistance of the bolt 9 in holding the ends of the band together on the wedge, which bolt also secures the wedge against slackening back and sustains at the joint the load of 45 the flume from the stringers. Simple band supports bolt-connected to the stringers are introduced at any desired distance intermediate the joint supports.

Having now particularly described my invention, I hereby declare that what I claim 50 as new and desire to be protected in by Letters Patent, is:

1. A flume construction, comprising the combination with a sheet metal flume and 55 the stringers between which it is carried, of means for jointing the upper edges of the flume to the inner adjacent sides of the stringers with a water-tight joint whereby the available carrying capacity of the flume 60 is increased by the amount which the stringers project above the edges of the flume, in-

ner and outer bands around the overlapping ends of adjacent flume lengths, and means for simultaneously applying compression to the inner and tension to the outer band. 65

2. A flume construction, comprising the combination with a sheet metal flume and the stringers between which it is carried, of means for jointing the upper edges of the flume to the inner adjacent sides of the 70 stringers, said means comprising a strip of jointing material interposed between each upper edge of the flume and the side of the adjacent stringer, a batten nailed to the stringer along the upper edge of the flume 75 and extending half over the flume edge, inner and outer bands around the overlapping ends of adjacent flume lengths, and means for simultaneously compressing the inner and applying tension to the outer band. 80

3. A flume construction, comprising in combination a sheet metal flume, the edges of which are jointed to the lower and inner sides of the stringers between which the flume is supported, means for jointing the 85 adjacent overlapping ends of the flume lengths, said means comprising inner and outer bands extending around the inner and outer surfaces of the overlapping ends, each end of each band having projections from 90 their adjacent sides, a cotted introduced between the bands and between their projections, and means for holding the bands together on the cotted.

4. A flume construction, comprising the 95 combination with a sheet metal flume and the stringers between which it is carried, of means for jointing the upper edges of the flume to the inner adjacent sides of the stringers with a water-tight joint whereby 100 the available carrying capacity of the flume is increased by the amount which the stringers project above the edges of the flume, inner and outer bands around the overlapping ends of adjacent flume lengths and means 105 for simultaneously applying compression to the inner and tension to the outer band and for securing them to the stringers. 110

5. A flume construction, comprising the combination with a sheet metal flume and 110 the stringers between which it is carried, of means for jointing the upper edges of the flume to the inner adjacent sides of the stringers with a water-tight joint, inner and outer bands around the overlapping ends of 115 adjacent flume lengths, and means for simultaneously applying compression to the inner band and tension to the outer band, and for securing the ends of the bands to the stringers and on the pressure applying means. 120

In testimony whereof I affix my signature.
HOWARD K. DUTCHER.
